ROD ELEVATOR

John Carlbert Cobb, Houston, Tex.

Application November 28, 1947, Serial No. 788,446

5 Claims. (Cl. 294—91)

1

This invention relates to improvements in rod elevators and refers more particularly to an elevator useable in conjunction with the installation of sucker rods or the like in a well bore and pulling such rods from a well bore.

In the producing of petroleum products from well bores a well often ceases to flow naturally and must be placed upon some suitable pump. Reciprocating pumps have been and are extensively used in such operations which necessitates the lowering of a string of rod joints within the flow tubing of the well. This rod string is called the sucker rod and extends to a lower level within the well bore to operate the pump plungers.

This invention is concerned with the device known in the industry as an elevator or rod elevator useable in the installation of such sucker rod in a producing well. The device may also be used to pull the sucker rod from the well, when required for any cause such as for instance to clean out the well, repack the plunger, or the like.

An object of this invention is to provide a simple rugged elevator which may be employed in operations of the character described.

Another object is to provide a rod elevator which may be easily secured to a rod and selectively released therefrom.

A further object is to provide a rod elevator wherein the latching mechanism for securing a rod in the elevator may be selectively retracted to and locked in non-operative position.

Still another object is to provide a rod elevator wherein the latching means for securing a rod in the elevator may be selectively secured in non-operative position and automatically tripped and moved to operative position when a rod is moved into gripping position relative to the elevator.

Other and further objects of the invention will appear from the description of the invention.

In the accompanying drawings, which form a part of the instant specification, which are to be read in conjunction therewith and wherein like reference numerals are used to indicate like parts in the various views:

Fig. 1 is an end elevation of an elevator embodying this invention and showing schematically the upper end of a string of flow tubing and the actuating cable of a well rig;

Fig. 2 is a side elevational view showing the elevator of Fig. 1 and also schematically illustrating the flow tubing and cable;

Fig. 3 is a sectional view taken along the line 3—3 in Fig. 1 in the direction of the arrows and illustrates the latching means in non-operative position; and

2

Fig. 4 is a view similar to Fig. 3 but showing the latching means in operative position.

Referring to the drawing, the numeral 5 designates the upper end of a string of flow tubing of a producing oil well. The numeral 6 indicates the uppermost rod length of a string of sucker rods being installed within the tubing. The elevator, indicated generally at 7, is secured to the length of sucker rod and the elevator in turn 10 is held by hook 8 secured to the lower end of cable 9. The cable 9 is a conventional part of the usual derrick or rig and will be understood by those skilled in the art.

The rod elevator 7 is made up of a body 11 having a wide mouthed slot-like side opening 11 extending therethrough. The wide throat or tapered extremity 12 of the opening facilitates access to the opening whereby a rod may be readily inserted therein. The dimensions of the 15 main portion of the opening are such that the body of the length of sucker rod is readily accommodated but the enlarged coupling at the end of the rod will not pass therethrough. The coupling seats upon the upper surface of the body 20 as shown in Figs. 1 and 2. The body carries pivot posts 13 to which the eye ends of bail 14 are secured. Suitable split rock rings 15 prevent accidental displacement of the bail ends from the pivot posts. The end flanges 16 on the body 25 serve to prevent the device from rotating on the pivot posts 13 when it is hanging free upon hook 8 and thus maintains the body properly oriented to receive a rod in opening 11. These flanges 16 also hold the elevator from assuming a position 30 such that the sucker rod might extend through the elevator and pass on the wrong side of the hook 8.

The latching means for securing a rod within side opening 11 is carried by the body. This 35 means includes plungers 17 slidably within bores 18 which communicate at one end with slot 11. The rear enlarged portions of the bores communicate exteriorly of the body and permit insertion of plungers 17. The flanges 17a and 17b of 40 the plungers fit the enlarged portion of the bore and provide a means for connecting the plungers with a trip mechanism to be hereinafter more fully explained.

It will be seen that the plungers are free to 45 move within bores 18 into position obstructing the opening 11 through the body. This is more clearly shown in Fig. 4. Also, it will be noted that the ends of plungers 17 present a V-shaped surface substantially centrally of the opening. 50 Due to this shape when the rod 6 is moved into position within opening 11, if plungers 17 are in

obstructing or operating position, the rod on contacting the V-shaped surface presented by the plunger ends will force the plungers toward retracted position permitting entry of the rod into opening 11.

A manually operable trip mechanism is provided for retracting plungers 17 to inoperative position. This mechanism includes two bell crank levers 19 pivoted between flanges 10a extending laterally from the side of body 10 opposite side opening 11. The pivot pins 20 for the levers are mounted in the flanges. One end of each of the crank levers carries a fork with rounded ends which ends fit between flanges 17a and 17b of the plungers. A spring 21 is connected between the arms of the bell crank levers remote from the plungers. This spring urges these arms apart and thereby urges plunger 17 toward operative or obstructing position within opening 11.

A mechanism is preferably provided for locking the trip mechanism to maintain the plungers in operative position. Toggle levers 22 and 23 joined together by a floating pivot and having their other ends pivoted to the arms of bell crank levers 19 adjacent their connection with the plungers are preferred for this locking function. The floating pivot of the toggle levers is free to move to the right to the position shown in Fig. 4 but its movement to the left is limited by engagement of the free ends of the bell crank levers with stops 26 extending between flanges 10a. Trigger 24 has a sliding movement within the body and has its one end exposed within opening 11 and the other end adapted to be engaged by the toggle levers as shown in Fig. 3. By reference to this figure it will be seen that with the toggle levers in the position shown the floating pivot is somewhat past center. This serves to lock the trip mechanism in the Fig. 3 position with plungers 17 retracted. To additionally secure this locked position a weak spring 25 is coiled about the floating pivot and has each end secured to one of the toggle levers. The tension of the spring is such as to urge the floating pivot toward trigger pin 24. Thus when the trip mechanism has been manually manipulated to retract plunger 17, the toggle levers lock the trip mechanism in this position until it is released by actuation of trigger 24. Obviously the trigger is tripped by engagement with a rod 6 when such a rod is passed into opening 11.

It is believed that the operation of the rod elevator is apparent from the foregoing description. When the rod elevator is to be secured to a rod 6 it is swung into position with the rod entering opening 11. Preferably plungers 17 have previously been retracted to their Fig. 3 position, but if this is not the case, nevertheless when the periphery of the rod engages the ends of plungers 17 the plungers are forced sufficiently toward retracted position to permit entry of the rod within opening 11. If the plungers had been previously forced to a retracted position by manipulation of bell crank levers 19, rod 6 upon entry into opening 11 will engage the inner end of trigger 24 forcing it against the toggle levers. Thus the floating pivot of the toggle levers will be displaced sufficiently to move the pivot past center so that spring 21 sharply moves bell cranks 19 about their pivots to advance plungers 17 into operative position obstructing the opening 11. In this position as shown in Fig. 4 rod 6 is secured within opening 11 and cannot accidentally be removed from the opening.

When it is desired to release the rod elevator

from a rod the operator manually forces the free arms of the bell crank levers together and into engagement with stops 26, thus compressing spring 21. This is effective to slide plungers 17 to their retracted position whereupon the rod elevator may be swung free from rod 6. The toggle levers retain the plungers in operative position until tripped by engagement with a rod when the elevator is again swung into operative position with a rod 6 within the opening 11.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof it is to be understood that all matter herein set forth or shown in the accompanying drawings is to be interpreted as illustrative and not in a limiting sense.

Having described my invention, what is claimed is:

1. A rod elevator comprising a body having a slot-like side opening extending therethrough, a latch member slidably mounted in the body and movable into and out of obstructing position relative to the opening, a spring operatively connected between the body and member urging the member toward obstructing position and manually operable means for selectively retracting the member from obstructing position, a locking means interposed between the manually operable means and the latch member for releasably locking said means in a position with the latch member retracted to non-obstructing position, and means for releasing said locking means whereby said spring may urge said latch member toward obstructing position.

2. A rod elevator comprising a body having a slot-like side opening extending therethrough, a latch member slidably mounted in the body and movable into and out of obstructing position relative to the opening, a spring operatively connected between the body and member urging the member toward obstructing position, manually operable means for selectively retracting the member from obstructing position, and locking means interposed between the manually operable means and the latch member for releasably locking said means in position with the latch member retracted to non-obstructing position and a trigger mounted in the body having a portion exposed within the opening adapted to be actuated by contact with a rod moved into holding position within the opening to release said locking means from locked position.

3. A rod elevator comprising a body having a slot-like side opening extending therethrough, two plungers slidably mounted in the body, one of the plungers on each side of the opening, said plungers adapted to extend into the side opening to obstruct the same and to be retracted out of obstructing position, two bell crank levers pivoted to the body and each having one end operatively connected to one of the plungers and their other end exposed exteriorly of the body, and a spring operatively connected between the levers to urge the plungers toward obstructing position whereby the plungers may

be selectively retracted from obstructing position by manual manipulation of the exposed ends of the levers.

4. A rod elevator comprising a body having a slot-like side opening extending therethrough, two plungers slidably mounted in the body, one of the plungers on each side of the opening, said plungers adapted to extend into the side opening to obstruct the same and to be retracted out of obstructing position, two bell crank levers pivoted to the body and each having one end operatively connected to one of the plungers and their other end exposed exteriorly of the body, a spring operatively connected between the levers to urge the plungers toward obstructing position, toggle levers pivoted to the bell crank levers and having adjacent ends connected by a floating pivot, the floating pivot of said toggle levers being free to move in one direction to permit movement of the plungers into obstructing position, stops carried by the body to limit movement thereof in the opposite direction, the traveling pivot when moved to extreme limited position being just off center whereby the plungers may be selectively moved to and locked in a 25 retracted position.

5. A rod elevator comprising a body having a slot-like side opening extending therethrough, two plungers slidably mounted in the body, one of the plungers on each side of the opening, said 30 plungers adapted to extend into the side open-

ing to obstruct the same and to be retracted out of obstructing position, two bell crank levers pivoted to the body and each having one end operatively connected to one of the plungers and their other end exposed exteriorly of the body, a spring operatively connected between the levers to urge the plungers toward obstructing position, toggle levers pivoted to the bell crank levers and having adjacent ends connected by a floating pivot, the floating pivot of said toggle levers being free to move in one direction to permit movement of the plungers into obstructing position, stops carried by the body to limit movement thereof in the opposite direction, the traveling pivot when moved to extreme limited position being just off center and a trigger mounted in the body engageable with the toggle levers when in locked position and having a portion exposed within the body opening engageable by a rod moved into the opening to trip the toggle levers whereby the spring and bell crank levers may urge the plungers to obstructing position.
